CAN OPENER

Harry V. Gould, Bridgeport, Conn.

Application June 17, 1933, Serial No. 676,305

4 Claims. (Cl. 30—3)

This invention relates to can openers, and more particularly, to the so-called wall type can openers wherein the mechanism may be secured to a wall, kitchen cabinet, or the like so that an operator's hand may be comparatively free for the loading and handle turning operation.

It is an object of the present invention to provide a can opener of simple design and one which will be economical to manufacture.

10 It is another object of the present invention to provide a can opener of the blade cutter and traction wheel type capable of holding large and heavy cans on the traction wheel better than those provided heretofore without a can supporting table or bottom support.

20 Some of the improved details of construction provided by the present invention are a blade cutter secured to the frame at a point far removed from its real cutting edge so as to be yieldable for irregularities in the rim of a can and means arranged to positively limit the yielding movement. Also, this latter means is adapted to prevent the can from tilting about the periphery of the traction wheel.

25 Another feature of construction includes the provision of a novel bracket arrangement wherein only a single screw is needed to lock and hold the main supporting arm rigidly in its operative position and about which the arm may be swung into and held in its inoperative position.

30 Still other features of the present invention are the provision of a novel arrangement for movably supporting a traction wheel on the frame and associated novel means for moving the traction wheel to and from operative and inoperative positions and for holding the wheel in these positions.

35 Other features and advantages will hereinafter appear.

40 In the drawing—

Figure 1 is a perspective view of the complete can opener of the present invention.

Fig. 2 is a front elevation of the main operating parts of the present invention, and shows the blade cutter punched into a can.

Fig. 3 is a side elevation of the main operating parts, showing the traction wheel in the raised operative position.

50 Fig. 4 is a side elevation of the main operating parts, on the handle side, in the raised operative position.

Fig. 5 is a view similar to Fig. 3, but shows the traction wheel in the lowered inoperative position.

Fig. 6 is a view similar to Fig. 4, but shows the handle parts in the lowered inoperative position.

Fig. 7 is a detail sectional view through the cutter and traction wheel, with these parts in the inoperative position on a can.

Fig. 8 is a view similar to Fig. 7, but shows the parts in the raised operative position on a can.

Fig. 9 is a perspective detail view of the bracket 16 and main arm in the operative position.

Fig. 10 is a view similar to Fig. 9, but shows the arm in its inoperative position.

Fig. 11 is a detail of the aligning studs.

Fig. 12 is a detail of the camming stud.

Fig. 13 shows the main operating parts of the present invention in position for cutting off rather than cutting out the top of a can.

Referring now in detail to the drawing, the present invention in its preferred form comprises a main frame 15 including a bracket 16 for attachment to a wall, kitchen cabinet, or the like, a horizontal plate or arm 17 and a vertical arm 18. The two latter arms are preferably located relative to each other by two aligning studs 19 on the vertical arm entering suitable cooperating apertures 20 in the horizontal arm, and are held together by screws 21 and 22.

Although it is possible to have the bracket 16 made integral with the horizontal arm 17, it is now considered preferable to have it made separate, as shown, so that the long forwardly projecting arm may be moved from a handy operating, but sometimes unsafe or in the way position (see Figs. 1 and 9) to a safe out-of-the-way position (see Fig. 10). In order to do this and to rigidly support the arms 17 and 18 in heavy load supporting and can cutting or operative position, the present invention provides a stud 23 and wing nut 24 and a tongue 25 on the bracket, with the tongue preferably lanced and formed integral therewith, and elongated slots 26 and 27 on the horizontal arm. The stud 23 fits into the slot 26 and the tongue 25 fits into the other slot 27.

When it is desired to move the frame from the inoperative position shown in Fig. 10 to the operative position shown in Fig. 9, it is merely necessary to loosen the wing nut 24 and swing the arm 17 around the stud 23 into the horizontal position, then slide it rearwardly on the stud as permitted by the slot 26 until the tongue 25 enters the slot 27, whereupon the nut is again tightened. Thus, the present invention provides a simple positive and very rigid connection.

The main operating parts of the can opener are located near the front end of the horizontal arm 17 and comprise a blade cutter 28 secured to the frame 15 by the screw 21. This screw also 5 serves to hold the vertical arm 18 to the horizontal arm 17. Preferably, this blade cutter is secured only at its upper end, at a point quite remote from the angular cutting edge 29 to be yieldable for irregularities in cans, as will be pointed out in 10 greater detail later.

A traction wheel 30 is also provided to engage the underside 31 of the rim 32 of a can 33, and provided with serrations or teeth 34 on its periphery adapted to bite into the can and move it 15 circularly about the blade cutter 28 while the latter cuts the top of the can, as may be seen best in Fig. 8.

According to the present invention, a simple, economical and very efficient mount is provided 20 for the traction wheel 30. This comprises a spacing collar 35 having a sliding fit in a vertical aperture 36 in the arm 18 and a threaded stud 37 having threaded connections 38 and 39 with the traction wheel and with a handle 40 respectively. 25 Thus, in assembling these parts to the frame, it is merely necessary to screw the stud 37 slightly into the handle, drop the spacing collar over the stud, pass this assemblage into the aperture 36, then thread the traction wheel onto the stud, and 30 solidly against the spacing collar 35.

This securing means may be, and preferably is, used to also hold a novel control cam 41 having a handle 49 to the frame 15. To this end the spacing collar 35 and stud 37 are made slightly 35 longer than the thickness of the arm 18, and the cam 41 preferably with a spring washer 48 are passed onto the collar before the traction wheel is threaded onto the stud, solidly against the spacing collar.

40 The control arm 41 in effect forms a carrier adapted to move the traction wheel 30 upwardly into the operative position under the rim 31 of the can 33, then move the can upwardly relative to the blade cutter 28 so that the angular cutting 45 edge 29 pierces into the top of the can, and to hold the traction wheel and associated handle 40 in either the raised operative position, Figs. 2 to 4 inclusive, or in the inoperative position shown in Figs. 5 and 6.

50 To this end, the cam is provided with a flat 42 spaced a short extent from the stud 47 to allow the spacing collar 35 and associated traction wheel 30 to move downwardly relative to the blade cutter 28 into the position shown in Fig. 5. 55 It is also provided with another flat 43 spaced a greater extent from the stud, which, when it engages the shelf 44, maintains the traction wheel in the raised operative position shown in Fig. 3. A convex section 45 is adapted to ride on the shelf 60 44 and convex section 46 is adapted to ride on the camming stud 47 to raise and lower the traction wheel relative to the cutter and shelf 44 as a handle 49 section of the cam is moved onto the shelf. It should also be noted that the flat 43 is offset slightly relative to the center line of the stud 37 (see Fig. 4) so that it is possible to lift 65 the traction wheel higher than the normal operative position; viz. higher than when the flat 43 and shelf 44 are parallel.

70 The vertical arm 18 is also provided with a tongue 50 preferably integral with the arm and arranged to be thrown at a right angle to the arm when the shelf 44 is formed. It serves to locate 75 and maintain a can spaced slightly from the face

of the traction wheel, as may be seen best in Fig. 2 in order to reduce friction.

It should be particularly noted that the present invention provides a novel form of yoke 51 overlying the blade cutter 28. Preferably, this yoke 5 is made U-shaped with a back section 52 having arms 53 engaging a side and integral fingers 54 underlying the main arm 17. It is held in place by the screw 22. This screw together with the blade screw 21 pass through the plate 17 and are 10 threaded into the other plate 18 to hold them on the locating lugs 19 and hold them rigidly together.

The arm 53 at the back of the blade cutter 15 serves to prevent the cutter from moving arcuately around the screw 21 and supports it against regular cutting strain while the back section 52 thereof has a lanced finger 56 adapted to limit the sidewise yielding movement of the cutter. If the yoke is formed with sharp bends on 20 the inside corners where the side arm 53 engages the back of the cutter, the back section alone may be spaced slightly from the cutter and it will not be necessary to provide a separate lanced finger 56.

The underside of the two arms 53 overlies the rim 32 of a can and serves to limit arcuate movement of the can about the traction wheel 30. The finger 54 section of the arms 53, by passing under the plate 17, locate the yoke vertically and prevent 30 it from shifting vertically when engaged by the top rim of a can.

Operation of the can opener is as follows—The underside 31 of the rim of a can 33 is hooked onto the teeth 34 of the traction wheel 30 while the 35 latter is in the lowered inoperative position shown in Figs. 5 and 6, or the can is moved over the cutter 28 as shown in Fig. 7, then the handle 49 is grasped and turned to the raised position shown in Fig. 4, whereupon the traction wheel 30 is moved 40 upwardly in the elongated slot 36 by the cam 41 riding on the shelf 44 and the blade knife 28 punches through the can as shown in Fig. 8.

The lower end of the yieldingly mounted blade 28 tends to keep the can rim on the traction 45 wheel 30 a maximum extent. The traction wheel is kept in the raised operative position, biting into the rim of the can, by the flat 43 on the cam engaging the shelf 44. It is merely necessary for the user to turn the handle 40, whereupon the 50 traction wheel turns the can past the blade 28 until the top is cut out either partially or fully, as preferred. Then the cam handle 49 is turned to the down position where the can can be removed from the traction wheel again.

In the raised position, it is absolutely impossible to remove the can because of the manner in which the blade 28 and traction wheel 30 co-operate, as may be clearly seen in Fig. 2. By having the cutter yielding at its lower end, it 60 may spring outwardly for bumps, seam sections, or other irregularities, yet the back section 52 of the yoke always prevents it from moving out far enough to allow the rim of even a heavy can from sliding off the traction wheel.

Although this can opener is preferably used for cutting out the tops of cans, as shown in Figs. 1 to 12, inclusive, and as described so far, it may also be used equally well for cutting off the tops of cans, by merely placing the frame in a flat-wise direction over the top of a can and with the traction wheel inside the rim section, then moving the cam 41 into operative position and turning the crank 40 as when cutting out the top of the can. Such application is shown in Fig. 13. 75

Other variations and modifications may be made within the scope of this invention and portions of the improvements may be used without others.

5 Having thus described the invention, what is claimed as new and for which it is desired to obtain Letters Patent, is:—

10 1. In a can opener, the combination of a frame; a traction wheel on the frame; a blade cutter adapted to locate and maintain the rim of a can on the traction wheel and at its lower end being yieldable with respect to the traction wheel for irregularities in the rim of the can; means for moving the traction wheel into engagement with the rim and to force said cutter through the top of the can; a crank for turning said traction wheel; a forwardly projecting arm forming a part of said frame; a U-shaped yoke with outer ends 15 in the form of feet to engage a side of the arm and other sections of the yoke being adapted to engage the rim of the can on both sides of the cutter; and fingers on the ends of the U-shaped yoke adapted to underlie the arm while the feet thereof engage the side of the arm to prevent the yoke from shifting relative to the arm when either side of the yoke is engaged by the rim of a can.

20 2. In a can opener, the combination of a frame, provided with an elongated slot; a blade cutter on the frame; a traction wheel and a shaft therefore having a sliding fit in said elongated slot in a direction toward and from said blade cutter; a shelf on said frame; a lug; and a cam pivoted on the traction wheel shaft having two flats, one spaced a short extent and the other spaced a long extent from the pivot adapted to rest upon the first-named shelf and maintain the traction wheel

in operative and inoperative positions relative to the blade cutter and also having two convex sections riding between the shelf and the said lug so as to move the traction wheel into and out of engagement with the rim of a can and force 5 the cutter into and out of the can.

3. In a can opener, the combination of a frame, provided with an elongated slot; a blade cutter on the frame; a traction wheel and a shaft therefore having a sliding fit in said elongated slot in 10 a direction toward and from said blade cutter; a shelf on said frame; a cam pivoted on the traction wheel shaft adapted to move the wheel to operative and inoperative positions relative to the rim of a can and to the blade cutter; and a flat 15 section on said cam adapted to rest upon the shelf and maintain the traction wheel in the operative position, said flat section being tangential to the pivot and being adapted to effect a secondary lift to the traction wheel from the 20 regular operative position to compensate for slippage in the regular traction bite and to compensate for slight irregularities in the can.

4. In a can opener, the combination of a frame including a vertical arm having an elongated 25 slot; a blade cutter secured to the frame; a traction wheel; and means for moving the traction wheel in said elongated slot toward and from said cutter blade, said vertical arm having at its lower end a right-angle bend forming a double tongue, 30 one of said tongues serving to locate the can relative to the cutter and traction wheel, and the other forming a shelf upon which the means for moving the traction wheel may work to shift the traction wheel relative to the cutter. 35

HARRY V. GOULD.
